(57) **CLAIM**

The ornamental design for an equestrian halter, as shown and described.

DESCRIPTION

FIG. 1 is a top, front, left perspective view of an equestrian halter, showing my new design;

FIG. 2 is a left-side view thereof;

FIG. 3 is a right-side view thereof;

FIG. 4 is a front view thereof;

FIG. 5 is a rear view thereof;

FIG. 6 is a top view thereof; and,

FIG. 7 is a bottom view thereof.

The broken lines shown in the drawings depict portions of the equestrian halter that form no part of the claimed design.

1 Claim, 7 Drawing Sheets

See application file for complete search history.
